Primary Examiner — Shawn T Gingrich*Assistant Examiner* — Bryan N. Melvin(74) *Attorney, Agent, or Firm* — BakerHostetler(57) **CLAIM**

The ornamental design for a high voltage crocodile clip, as shown and described.

DESCRIPTION

FIG. 1 is a front elevation view thereof;

FIG. 2 is a right side elevation view thereof;

FIG. 3 is a left side elevation view thereof;

FIG. 4 is a bottom plan view thereof;

FIG. 5 is a top plan view thereof;

FIG. 6 is a rear elevation view thereof; and,

FIG. 7 is a perspective view thereof.

The broken lines in the drawings illustrate portions of the high voltage crocodile clip that form no part of the claimed design.

1 Claim, 7 Drawing Sheets(56)
